UNITED STATES PATENT OFFICE

ROBERT H. ROARK, OF WACO, TEXAS, ASSIGNOR, BY MESNE ASSIGNMENTS, TO THE GENERAL ICE SCORING MACHINE COMPANY, OF DALLAS, TEXAS, A CORPORATION OF DELAWARE

MEANS FOR SCORING ICE BLOCKS BY FLUID PRESSURE

Application filed November 25, 1927. Serial No. 235,512.

This invention relates to ice cutting machines and more particularly to machines of this class for scoring or making kerfs in blocks of ice so that the block may be afterward separated into smaller blocks or cakes of a predetermined weight, for convenient handling and distribution.

The improved machine provides mechanisms and parts for the utilization of fluid pressure for lowering movable saws for cutting kerfs in a block of ice cross-wise of the block and for moving the block by fluid pressure means between saws for scoring it and making kerfs therein longitudinally of the block and removing the block from the machine.

With the above and further objects in view the invention will be fully understood from a perusal of the following detailed description taken in connection with the accompanying drawings and wherein:

Figure 1 represents a partial side elevational view of the machine.

Figure 2 is an end elevational view.

Figure 3 is a longitudinal sectional view of a double-acting cylinder and a cross-section of a valve at the bottom of the machine.

Figure 4 is a side view of a valve disk and its control rod, the latter being in section.

Figure 5 is a longitudinal sectional view of a single action cylinder and a cross-section view of its operating valve, at the top of the machine; and

Figure 6 is a side view of a valve disk and sectional view of its rod for controlling the single action valve.

A more particular and specific reference will now be made to the various parts of the invention and different numerals will be utilized to so designate these parts. The numeral 1 denotes the flooring of a building within which the machine is placed. Formed in the flooring is a longitudinal opening 2 for the purpose of allowing the passage of an element, hereinafter referred to, for moving the ice through the machine.

Mounted upon the flooring 1 are four upright members 3, formed of channel iron or the like, the groove of the channels being toward the center as shown in Figure 2. The

purpose of these channels will be fully explained hereinafter. Suitable brace members 4 connect the side pairs of uprights and similar brace members 5 extend across the ends.

Movably suspended between the uprights 5 is a carriage member indicated generally at 6 and which consists of a rectangular frame 7 with a downwardly projecting member 8 at each corner thereof. Suitable braces 9 connect the members 8 and with the diagonal braces 9 form a rigid structure. Seated upon the carriage is a motor 10, and as will be obvious the latter occupies a position above the frame 7, clearly shown in Figures 1 and 2.

Formed at the lower extremity, at the inside of each of the members 8 is a bearing 11, opposite pairs of bearings being arranged in alinement, the pair at one side of the said carriage having mounted therein the shaft 12, and the pair at the opposite side of the carriage carrying the shaft 13. Each of these shafts carry circular saws 14 and 15. It will be seen by reference to Figure 2 that the teeth of the saws 14 are set at the reverse position to those on the saws 15 so that each set of saws in order to cut properly must be rotated in the direction indicated by the arrows in Figure 2. The saws are caused to rotate by means of the shaft 16 on motor 10 by means of the belts 17 and 18, the latter belt being twisted as shown to cause the saws 15 to rotate in a direction opposite to that of saws 14. Rollers 19 which ride in the grooves of the channel irons or members 3 enable the carriage to be moved upwardly and downwardly as will be referred to hereinafter.

Supports 20 are provided for a motor 21 which drives the shafts 22 and 23 upon which are mounted saws 24 and 25 on opposite sides of a block of ice A for scoring the ice longitudinally. A guideway 26 enables the ice to travel in alinement with the saws.

For the purpose of moving the carriage upwardly and downwardly to score a block of ice cross-wise there is provided a cylinder 27 which operates by fluid pressure. This cylinder has a piston 28, see Figure 5, and piston rod 29. There is also included in the arrangement for moving the carriage a counterweight 30 suspended by a cable 31 connected to the

piston rod 29 and a cable 32. Both cables are connected to the counterweight, the cable 32 being also fastened to the carriage 6 and riding over pulleys 33, the cable 31 riding over the pulley 34.

Fluid pressure is admitted into the cylinder 27 from any suitable source by the pipe 35 and is controlled by a valve 36 of a three-way type, the cylinder being of single action. The valve includes a disk 36 having a notch 37, see Figure 6, the disk being moved manually by a rod 38 having an operating handle 39. Adjacent the disk is an arm 40 so pivoted to the framework as to occupy positions shown in full and dotted lines. The valve 36 is returned to normal position by a spring 41. On one end of the piston rod 29 is a member 42. The operation of this cylinder and valve and co-acting parts will be fully explained herein-after.

The foregoing relates to the means employed in connection with fluid pressure for moving the rotating saws in scoring the ice blocks cross-wise. For moving the ice blocks between the saws 25 to score the block longitudinally a double-acting cylinder 42, shown in detail in Figure 3 is disposed at the bottom of the machine. This cylinder includes a piston 43, piston rod 44 and ports 45 and 46 and a four-way valve 47, including a valve disk 48. A pipe 49 feeds the valve with liquid pressure. This cylinder is operable in conjunction with the counterweight in moving the ice block A between the saws 25 to score the block longitudinally. The valve co-operates with the counterweight by means of a lever 50 in connection with a link 51 loosely secured to the disk 48. Connected to the piston rod 44 is an ice pusher 52 held in normal upright position by spring 53.

In practical operation of the machine, when the operator places a block of ice in the machine in position for scoring the block, he pulls the operating lever 38 so as to rotate the valve disk 36 until the finger 36^a comes into the notch 37. The valve 36 (normally held closed by the spring 41) opens, admitting fluid pressure into the cylinder 27 and moving the piston rod 29 in direction of arrow 50 and thus raising the counterweight 30 by means of the cable 31. This permits the saw carriage 6 to descend, the rotating saws score the block vertically.

When the saws have reached the bottom of edge of the ice block, the member 42 on the piston rod 29 has moved far enough to the right in Figure 1 to come into contact with the upper end 40^a of the arm 40, and the finger 36^a is thrown out from the notch 37 and the spring 41 retracts the valve to closed position—cutting off fluid pressure from the cylinder 27, and at the same time releasing the pressure therein.

The fluid pressure no longer supporting the counterweight, which is heavier than the saw

carriage, the counterweight descends to the position shown in Figure 1, raising the saw carriage to former position.

The cylinder disposed at the bottom of the machine is of a double-acting type and is supplied with fluid pressure by means of the four-way valve 47, see Figure 3, this valve being controlled by the lever 50, and spring 50^a. Now when the counterweight 30 is at its lowermost position it rests upon and depresses one end of the lever 50, thereby raising the opposite end thereof which end is heavier and through the link at 51, places the valve 47 in position to admit pressure to the left end of the cylinder in Figure 3 and thereby moving the piston 43 to the right. The pusher is then in the position indicated at 52' and is behind the ice block which has been moved to position A' having passed between the saws 24 which have scored the block longitudinally. The pusher is hinged to the rod 44.

When the counterweight is lifted as above described the weight of same is removed from the lever which assumes the dotted-line position in the drawing, the weight 42' causing the right hand end thereof to move downward, assisted by the spring 50^a attached to the disk 48. When the heavy end of the lever is down the position of the valve is reversed, releasing pressure from left end and admitting pressure to the right end of cylinder 42, causing piston rod 44 to move to the left in fully extended position, the hinged pusher passing under the ice block readily and when out from under the block, the spring 53 retracts it to an upright position.

After the rod 44 has removed the ice from the machine, another block can be placed therein and the operation repeated.

It will be readily seen that fluid pressure means could be used to move ice blocks into the machine as well as to remove them and that the ice block could be scored horizontally as it entered the machine instead of as it leaves the machine.

Further modifications could be had such as would enable all the valves to be automatically controlled, or all valves manually controlled as desired.

What is claimed as new is:

1. In an ice scoring machine having vertically movable scoring means adapted to score a block of ice during such movement, fluid pressure means for effecting said vertical movement, and automatically operated means for cutting off and releasing fluid pressure when the vertical movement in one direction is completed, whereby the scoring means may return to its initial position.

2. In an ice scoring machine having vertically movable scoring devices adapted to score a block of ice during such movement in one direction, fluid pressure means for effecting said vertical movement, manual means

for initially supplying the fluid pressure, and automatic means for cutting off and releasing the fluid pressure as soon as the vertical movement in one direction is completed, 5 whereby the scoring means may return to its initial position.

3. In an ice scoring machine having vertically movable scoring means, and stationary horizontal scoring means, fluid pressure 10 means for effecting vertical movement of the scoring means for vertically scoring a block of ice, means for automatically cutting off and releasing the fluid pressure as soon as the vertical scoring operation is completed, 15 whereby the scoring means may return to its initial position, fluid pressure means automatically operating to advance the blocks of ice in contact with the horizontal scoring means when the vertical scoring means has 20 been restored to initial position, and means for automatically cutting off and releasing the fluid pressure from the block advancing means as soon as the horizontal scoring operation is completed.

25 4. An ice scoring machine comprising a framework, a carriage movably arranged in the framework and carrying saws, fluid pressure means for moving said carriage in a vertical plane to score ice blocks vertically, 30 means for automatically cutting off fluid pressure when the vertical scoring operation is completed, stationary saws for sawing the ice horizontally, means for moving by fluid pressure the blocks of ice between the stationary saws to effect the horizontal scoring and for delivering the blocks from the machine, said ice moving means operating automatically after the vertical scoring operation is completed, and means for automatically cutting off and releasing the fluid pressure from said ice moving means as soon as the horizontal scoring has been completed.

5. In an ice scoring machine having vertically movable scoring means adapted to 45 score a block of ice during such movement, fluid pressure means for effecting said vertical movement, and means movable with said vertical scoring means for automatically cutting off and releasing fluid pressure when the 50 vertical movement in one direction is completed, whereby the scoring means may return to its initial position.

6. In an ice scoring machine having vertically movable ice scoring means, and horizontal ice scoring means, fluid pressure operated means for effecting vertical movement of the scoring means for vertically scoring a block of ice, fluid pressure operated means for advancing the blocks of ice into contact 55 with the horizontal scoring means, manual means for initially supplying fluid pressure to one of said fluid pressure operated means, and automatic means for supplying fluid pressure to the other of said fluid pressure 60 means when the one has completed its move-

ment, and means for automatically cutting off and releasing fluid pressure from each of said fluid pressure operated means when its respective movement is completed.

In testimony whereof I affix my signature. 70

ROBERT H. ROARK.
